SWAGING MACHINE

John L. Marsh, North Tonawanda, N. Y.

Application October 28, 1943, Serial No. 507,997

1 Claim. (Cl. 78—21)

This invention relates to a swaging machine of the type in which one or more pairs of swaging dies are moved radially toward and from the article to be swaged at the same time that they are carried bodily around said article.

In machines of this character, as heretofore constructed, the members of each pair of dies have usually been slidable radially in guideways on a rotary carrier, which guideways have two circumferential guide walls arranged on the carrier and engaging with the correspondingly opposite sides of the dies, a fixed rear wall engaging with the rear side of these dies, and a removable front guide wall engaging with the front side of these dies and detachably connected with the carrier.

Whenever it became necessary to remove one of these dies from its guideway it has been customary heretofore to first remove the front guide wall and then drive the respective die out of its guideway by hitting the same manually from the rear of the carrier which operation was not only inconvenient but also time consuming because it required the operator to get in the rear of the machine, as well as the front thereof, when it became necessary to remove a die.

It is the object of this invention to provide a machine of this character with means whereby the removal of a die from its guideway in the rotary carrier is effected automatically and preferably by spring pressure, thereby facilitating this operation and not only avoiding the loss of time heretofore required for this purpose, but also enabling the work to be done more conveniently and easily.

In the accompanying drawing:

Fig. 1 is a vertical longitudinal section of a swaging machine equipped with this invention.

Fig. 2 is a fragmentary front elevation thereof with some parts omitted.

Fig. 3 is a fragmentary vertical longitudinal section, on an enlarged scale, taken on line 3—4, Fig. 2, and showing the members of a pair of cooperating dies in their working position on the carrier which rotates them and guides them relative to the workpiece which is being operated upon.

Fig. 4 is a similar view showing one of the dies of a pair projecting forwardly from its operative position by means of this invention.

Figs. 5 and 6 are fragmentary cross sections taken on the correspondingly numbered lines in Fig. 2.

Fig. 7 is a side elevation of a cable which is provided at its opposite ends with terminals

adapted to be secured thereto by a swaging machine which is provided with this invention.

In the following description like reference numerals indicate the same parts in the several figures of the drawing.

An example of the work performed by this machine is shown in Fig. 7 which represents a cable 10 of wire strands which are twisted together and two terminals or fittings which are arranged at opposite ends of this cable and each having an inner tubular sleeve 11 secured to one end of the cable by swaging the sleeve thereon and an outer eye 12 or like part adapted to be connected with some other member.

The numeral 13 represents a stationary head which forms part of the frame of the machine and which is provided with a horizontal circular opening 14 containing the elements whereby the swaging operation is performed. Within the opening 14 is secured a ring 15 the bore of which forms a cylindrical track or runway which is engaged by the outer side of an annular row of hammer or operating rolls 16 and upon which the latter rotate about their individual axes and also move bodily around the axis of this ring during the operation of the machine.

Within the runway ring or annular track is arranged an annular roll rack or cage 17 which rotates about a horizontal axis parallel with the axes of the operating rolls and which is provided with an annular row of pockets 18 each of which is open on its radial outer and inner sides and also open at its front end. In each of these pockets one of the operating rolls is loosely mounted so that the same is free to rotate and bears with its outer side against the bore of the runway ring 15 while the inner side of the same projects slightly beyond the inner side of the rack or cage. The rear end of each roll bears against the closed

rear end of the respective pocket 18 in the roll cage while its front bears against a front annular wear plate or ring 19 which is arranged in front of this cage. The front wear ring and the roll cage engage their peripheries with the bore of the runway ring and are free to slide circumferentially thereon. The front wear ring engages with the inner side of a front face plate 20 of circular form secured to the front side of the frame head. The rear side of the roll cage or rack engages with a rear wear plate 21 of circular form and capable of sliding circumferentially thereon. This rear wear plate is mounted on a bearing plate 22 secured to the rear side of the frame head.

Centrally within the space bounded by the an-

nular row of operating rolls, and the rack or cage and the front wear plate is arranged a rotary die carrier or holder 23 which is provided on its rear side with a spindle 24 whereby the same is supported and driven. This spindle is journaled in a bearing 25 on the rear bearing plate 22 and is rotated by means which include a belt 26 passing around a driving pulley 27 secured to the rear part of the spindle, as shown in Fig. 1.

Upon the carrier are mounted one or more pairs of forming dies 28, one of such pairs being shown, for example, in the present case. The members of this pair of dies are slideable radially on the carrier on diametrically opposite sides of the axis of the carrier and are adapted to engage their inner ends or faces with opposite sides of the workpiece for shaping or reducing the latter. These dies are guided in radial guideways arranged diametrically on opposite sides of the carrier, these guideways having two fixed circumferentially opposite longitudinal guide walls 29, 29 which are formed on the body of the carrier, a rear fixed guide wall 30 which is formed on the rear part of the carrier, and a detachable front wall which consists of a central section 31 secured by screws to the carrier across the inner parts of the guideways, and two outer sections 32 secured by screws to the front side of the carrier across the outer parts of these guideways. Linings or wearing plates 33 may be interposed between the longitudinal and rear sides of the dies and the respective guide walls of the carrier for taking up wear and also varying the size of the dies to be used. The central section of the front guide wall is provided with a central guide opening 34 whereby the workpiece is guided in a central position between the dies. Within the outer parts of these guideways backer blocks or kickers 35 slide radially, each of these blocks engaging its inner end with the companion die in the inner part of the respective guideway and the outer end of the same being engaged by the several hammer rolls. Each of these kicker blocks is held in place within the outer part of the respective radial guideway by one of the front guide wall sections 32.

On the front side of the frame head a gate 36 is mounted to move toward and from the die carrier and provided with a central conical guide opening 37 for guiding the workpiece into the guide opening of the front guide wall of the dies.

During the operation of the machine the rotation of the die carrier causes the outer ends of the backing blocks to be engaged successively by the several hammer rolls whereby the latter and the dies are intermittently kicked inwardly with a cam action and thrown outwardly by centrifugal force and a succession of hammer blows are delivered continuously by the dies against opposite sides of the workpiece which has been placed between the dies. As each hammer roll is engaged by a backing block the same is rolled slightly on the circular runway thereby causing the roll cage or rack to shift its position circumferentially step by step in a manner well known in this type of swaging machine.

When the cable only requires a terminal at one of its ends the cable is usually inserted between the dies by passing the cable rearwardly between the dies with the opposite inner end of the cable in advance until the sleeve of the terminal is between the dies, as shown in Fig. 3, after which this sleeve is contracted or reduced in diameter by operating the machine and caused to grip the outer end of the cable so as to be securely

connected therewith. After the terminal has been thus secured to the outer end of the cable the same is withdrawn forwardly from between the dies and replaced by another cable and terminal 5 of this character without requiring either of the dies to be shifted out of their normal position from the rotary carrier. Other work of a like character having a narrow body and an enlarged member or fitting at only one end thereof may be similarly connected by the swaging operation between the dies of this machine. When, however, it is necessary to swage two members, which are of larger diameter than the width of the gap between the dies while the same are in an open position, and which in the finished product are arranged on opposite sides of a thinner or narrower body, such as attaching comparatively wide terminals to opposite ends of a narrow cable of the character shown in Fig. 7, it is customary to 10 first attach a terminal to the outer end of the cable while its inner end is free, in the manner described. Thereafter the cable is withdrawn from between the dies and reversed so that the end thereof having the terminal attached thereto 15 is innermost and then passed rearwardly through the space normally occupied by the dies. In order, however, to permit of doing this from the front side of the machine at least one of the dies has to be removed either wholly or partly from the respective guideway on the die carrier to provide the required clearance and this has usually been accomplished by first moving the gate 36 away from the front side of the die carrier, then moving the central detachable 20 guide wall section 31 from the die carrier and then pushing the respective die forwardly either wholly or partly out of its guideway by means of a tool engaging the rear side of this die. This manner of removing a die from the die carrier 25 is not only very inconvenient but it also slows up production on account of the loss of time and the undue stoppage of the machine. After the second terminal has been swaged on the outer or front end of the cable it becomes 30 necessary to again temporarily remove one of the dies of a pair either wholly or partly inasmuch as the normal gap between the dies 28 when farthest apart does not furnish adequate room for this purpose, thereby further inconveniencing the operator and wasting time and preventing work of this character from being 35 done in the most economical manner.

Means have therefore been provided in accordance with this invention whereby, upon disconnecting the central section 31 of the front wall from the die carrier, the respective die will be automatically projected forwardly from its guideway a sufficient extent that its complete removal can be effected manually, if necessary, by grasping the front end thereof, and withdrawing this die forwardly from its guideway either wholly or as much as may be necessary.

Although this result may be accomplished by various means, those shown in the drawing are preferred on account of their simplicity of construction, the certainty of their operation, and their freedom from liability to get out of order.

As shown in Figs. 1, 3, 4 and 6, these automatic die ejecting means comprise a longitudinal pocket or recess 38 formed on the rear side of one of the dies and a helical compression spring 39 arranged in said recess and having its front or inner end bearing against the bottom of this recess and its outer or rear end bearing against the adjacent 70 part of the rear wear plate or liner 33.

When assembling the dies of a swaging machine employing an automatic ejecting device of this construction that one of a pair of dies having no ejecting spring associated therewith is first slid rearwardly into its respective guideway in the die carrier, then the companion die having a recess 38 with a spring 39 therein is inserted in its guideway and pushed rearwardly until its rear side bears against the corresponding side of this guideway thereby compressing the ejecting spring 39, then the front wall section 31 of the guideways is secured to the die carrier, thereby holding both dies in their normal operative position in their guideways.

While the parts of the swaging machine are in this position fittings, such as terminals, may be swaged onto one end of a cable without removing a die from the die carrier inasmuch as such articles can be readily inserted between the dies and also removed therefrom, after being finished, from the front side of the machine without requiring any dismantling of the machine.

When, however, it is necessary to provide sufficient clearance space to permit of passing a fitting from the front side of the machine rearwardly through the space normally occupied by the dies the central section of the front wall of the die guideways is detached from the die carrier and when this is done the resilience of the ejecting spring 39 immediately pushes the spring loaded die forwardly out of its guideway a sufficient extent, as shown in Fig. 4, so that this die may be grasped manually and then a complete removal of the same may be effected without the use of a tool at the back of the machine.

After the spring loaded die has been moved forwardly either completely out of its guideway, or sufficiently to provide the necessary clearance, that end of a cable or the like having a terminal or like fitting previously secured thereto may be passed rearwardly through the gap between the dies, as shown by dotted lines in Fig. 4, after which the respective spring loaded die may be again pushed rearwardly into its normal position within its guideway and retained therein by restoring the front wall section 31 of this guideway, thereby permitting resumption of the operation of swaging a like terminal on the front end of the cable, as previously described with reference to the showing in Fig. 3.

When the second terminal has been thus secured to the front end of the cable in addition to the one at its rear end, it again is necessary to widen the space between the dies to permit the narrow cable with its wide rear terminal or fitting to be withdrawn forwardly from the machine, and this is accomplished in the same man-

ner as that described with reference to preparing the die means for permitting a cable having an enlargement, such as a terminal, at its advancing end to be passed rearwardly through the die gap.

The passage of a terminal or other fitting through the gap between the dies when one of them is not wholly withdrawn from the carriage is possible when the recesses on the faces of the dies are of a depth or form which will permit such use, but if partial withdrawal of a die does not provide the required clearance then the respective die must be removed in its entirety, before a fitting can be moved through this clearance space opposite the face of the remaining die.

Owing to the convenience and rapidity with which the die means of a swaging machine can be opened or widened to permit the enlarged parts and narrow parts of articles to be passed backwardly and forwardly through the die gap without requiring the operator to reach behind the machine for this purpose, the operation of doing work of this character is facilitated and the output materially increased, thereby effecting a substantial economy in cost of doing work of this character.

I claim as my invention:

A swaging machine comprising a supporting head provided on its inner side with an annular track, an annular row of operating rolls having their outer sides in rolling engagement with said track, a rotary rack arranged within said track and provided with an annular row of pockets each of which contains one of said rolls, a rotary carrier arranged within said rack and provided with a pair of radial guideways arranged on diametrically opposite sides of its axis, each of said guideways having two circumferentially opposite guide walls which are fixed relative to the carrier, a rear guide wall which is fixed relative to the carrier and a front guide wall which is detachably connected with the carrier, and spring means for automatically ejecting one of said dies forward from its guideway when said front guide wall is detached from said carrier, said spring means including a recess formed on the rear side of the respective die, and a helical spring which is arranged in said recess and bears at its front end against the bottom of said recess and at its rear end against the adjacent part of said rear guide wall and which is compressed when the respective die is moved backwardly into its guideway but which expands and pushes said die forwardly in its guideway when the front guide wall is detached from the carrier.

JOHN L. MARSH.
